UNITED STATES PATENT OFFICE.

HARRY C. ROPER, OF ST. LOUIS, MISSOURI.

COMBINED TOBACCO-CAN AND MATCH-BOX.

1,209,208.

Specification of Letters Patent. Patented Dec. 19, 1916.

Application filed February 10, 1915. Serial No. 7,399.

To all whom it may concern:

Be it known that I, HARRY C. ROPER, a citizen of the United States, and resident of St. Louis, Missouri, have invented certain new and useful Improvements in Combined Tobacco-Cans and Match-Boxes, of which the following is a specification containing a full, clear, and exact description, reference being had to the accompanying drawings, 5 forming a part hereof.

My invention relates to improvements in combined tobacco cans and match boxes, wherein a tobacco can is provided with a fixed bottom and a movable bottom, so that 15 there may be held therebetween matches and the like, the primary object of my invention being to construct a single container for both tobacco and matches, and to provide locking means for the closures of each re- 20 ceptacle, so that when one closure is open the other may be locked against opening.

To the above purposes, my invention consists in certain novel features of construction and arrangement of parts which will 25 be hereinafter more fully described, pointed out in my claims, and illustrated in the accompanying drawing, in which—

Figure 1 is an elevation of a tobacco can and match box embodying my improvements; Fig. 2 is a vertical, sectional elevation of the device taken on the line 2—2 of Fig. 1; Fig. 3 is an inverted plan of the device; and Fig. 4 is a fragmental, longitudinal sectional elevation taken on the line 35 4—4 of Fig. 3.

Referring by numerals to the accompanying drawings: 5 designates the body portion and 6 the hinged lid of a conventional tobacco can. Formed in the body of the 40 can near its open end and opposite to its point of hinging with the lid there is formed a boss 7, and in the lid 6 there is formed a similar boss 8. These bosses are both formed by being struck from the can and 45 lid respectively, and serve to form a snap lock. Adjacent the lower end the can body is provided with an outstanding bead 9, which extends around the major portion of the can only, the can body from the ends of 50 said bead being removed, as shown at 10 in Fig. 1.

11 designates the can bottom, which is of inverted cup shape and provided with an outstanding bead 12 which engages in the bead 9 of the can body and from said bead 55 12 the walls 13 of the bottom extend to a crimp 14 which embraces the lower raw edge of the can body. This wall 13 and its crimped portion 14 are cut away, as is the can body at 10.

15 designates the removable bottom or closure for the match box which match box is formed by said inverted cup shaped bottom proper and the lid 15. This closure 15 slides between the beads 12 of the bottom 65 11 and has at its free end a wall 16 which is the counterpart of the lower end of the can, including the bead 9. This wall 16 serves as a handle or gripping portion for 70 the manipulation of the closure 15. In order to secure the closure 15 in a closed position there is formed by striking from its material a boss 17, which frictionally engages the lower margin of the can, as shown in Fig. 4. This lid carries a roughened 75 surface 18 for convenience in striking matches. Primarily this box is designed for use in carrying matches for the convenience of the smoker, but I have found that this space between the two lids may contain a 80 blotter device, as shown by dotted lines at 19 in Fig. 2. In order that the moisture from said material may enter the body of the can, there are provided the perforations 20.

Having thus described my invention, what I claim as new therein and desire to secure by Letters Patent of the United States is—

1. In a combined tobacco can and match box, a can, a closure therefor, a can bottom spaced from the ends of the can, the said walls of said can and said bottom being partially removed, a closure near the open end of said bottom, means for slidably connecting said closure with said bottom, said 90 closure carrying a counterpart of the wall removed from the bottom of the can.

2. In a combined tobacco can and match box, a can, a closure therefor, a can bottom spaced from the ends of the can, the said 100 walls of said can and said bottom being partially removed, a closure near the open end

of said bottom, means for slidably connecting said closure with said bottom, said closure carrying a counterpart of the wall removed from the bottom of the can, and
6 means for independently locking said closures of the can and bottom.

In testimony whereof, I have signed my

name to this specification, in presence of two
subscribing witnesses.

HARRY C. ROPER.
